UNITED STATES PATENT OFFICE

LUCIUS D. COPELAND, OF CAMDEN, NEW JERSEY.

STEAM-GENERATOR.

SPECIFICATION forming part of Letters Patent No. 394,461, dated December 11, 1888.

Application filed November 19, 1887. Serial No. 255,635. (No model.)

To all whom it may concern:

Be it known that I, LUCIUS D. COPELAND, a citizen of the United States, residing at Camden, in the county of Camden and State of New Jersey, have invented certain new and useful Improvements in Steam-Generators; and I do hereby declare the following to be a full, clear, and exact description of the invention, reference being had to the accompanying drawings, which form part of this specification.

My invention has relation to certain improvements in the type of safety steam-boilers constituting the subject of Letters Patent of the United States No. 360,759, issued 15 to me the 5th day of April, A. D. 1887, and specially designed for use on steam-tricycles, pleasure-boats, and small vehicles and vessels.

My invention consists in the novel construction, combination, and arrangement of parts, hereinafter described, whereby the efficiency of the boiler is increased and the rapid generation of steam promoted.

In my Patent No. 360,759 I have shown and 25 described a form of tubular boiler especially designed and adapted to be heated by means of liquid fuel, although solid and vaporized fuel may be used when desired. In such patented steam-boiler the shell consists of two 30 main cylinders connected by a conical non-conductor to retain the heat. Within the upper main cylinder or cylindrical sections are arranged a number of smaller cylinders having fire-flues and communicating with each 35 other by means of short pipes entering their steam and water-spaces, so as to produce a circulation between them.

The improvements hereinafter described 40 contemplate the adoption and use of the general form and arrangement of parts described and shown in the patent referred to, with such slight modifications as the additional features constituting my invention render expedient.

45 Referring to the accompanying drawings, Figure 1 is a vertical central section of a boiler embodying my invention; Fig. 2, a plan view of a modification; Fig. 3, a perspective view of a water-leg, and Fig. 4 a similar view of one of the cylinders. Fig. 5 is a 50 section through a portion of the boiler shell or casing.

A A', Fig. 1, represent the two main cylinders, connected by a conical section, B, which parts constitute the external shell or casing 55 of the boiler. Within this shell, at a slight distance therefrom, is another shell, C C', of like form and contour. Both shells are lined with asbestos, as shown at D, or with other equivalent non-conducting material, to confine and prevent the radiation of heat. The non-conducting material is secured to the metal of the casings by suitable rivets or bolts, d. Between the asbestos lining of the shell A A' and the surface of the shell C C' is 60 left a space, D', which surrounds the entire shell C C', and which is designed to form an air-space having inlet apertures or slots d in the base or bed-plate A² of the boiler. The object of this space is to permit of a free circulation of air between the two shells and prevent as far as possible the communication 70 of heat to the outer shell.

As will be seen, the two shells or casings extend across the top of the boiler and form a 75 dome, A³, which confines the heat, preventing its upward radiation and permitting of the location of the boiler below the seats of boats or vehicles. Within the main cylinders are a 80 number of steam-generating cylinders, E E', &c., any number of which may be used, though I have illustrated a central cylinder, E, with surrounding cylinders E', to correspond with the arrangement shown in said patent.

The cylinders E' have fire-flues e extending 85 from end to end, and drop or pendent water legs or tubes f f', which extend from the bottoms of the cylinders, as shown, down into the lower cavity or chamber of the main cylinder or casing, the latter constituting the combustion-chamber, in which is located a grate, atomizer, or other adjunct for burning fuel, either solid, liquid, or gaseous.

The central cylinder, E, may have six fire-flues and one central water-leg, f', while the 95 surrounding cylinders, E', may have each five fire-flues and three water-legs; but the number of flues and water-legs may be varied and their location changed.

In my Patent No. 360,759 the water-legs of 100 the cylinders are simply plain cylindrical tubes, but I now provide each tube with an external longitudinal flange or web, g, for the purpose of increasing the heating-surface,

These flanges are arranged in vertical planes, so as to offer no obstruction to the free passage of the flames upward. These flanges may be in the form of continuous webs; but to compensate for expansion and contraction I prefer to divide them into short sections by means of horizontal kerfs or slits g' , cut at regular intervals. I also arrange within each water-leg a supplemental concentric tube, g^2 , of sufficiently small diameter to leave a water-circulation space, h , between the two, communication being had between the interior of the tube g^2 and the water-leg at the bottom through notches g^3 , cut in the lower end of the supplemental tube. As the water in the leg becomes heated its tendency is to rise in the space h toward the cylinder. This allows the water in the supplemental tube to descend and take its place in the space h , thus keeping up a constant circulation and producing rapid heating and generation of steam.

The central cylinder, E, I have found it expedient to elongate, in order to increase its capacity and enlarge its heating-surface. Accordingly I extend it both above and below the ends of the surrounding cylinders, the upper end entering or nearly entering the dome of the casing. The connections of the central cylinder with the water or steam space of the outer cylinders are made by means of tubes i rising from the upper ends of the outer cylinders and entering the side of the central cylinder. The tube-couplings are such as will allow of connection and disconnection being easily made. The outer cylinders are also connected to and their water-spaces in communication with the central cylinder near the lower end of the former by means of transverse or horizontal branches i' .

The water-leg of the central cylinder differs from that shown in my patent in being extended through the center of the cylinder to near the top thereof and provided with an internal supplemental tube, k , terminating a short distance from or above the lower end of the water-leg and extending above the cylinder. At its upper end this tube is connected to a drum or steam-cylinder, L, from which steam is taken for consumption. The steam from the outer cylinders entering the central cylinder, wherein its temperature is raised, enters the water-leg through the top, and thence passes downward and into the supplemental tube, through which it is conducted to the engine by pipe L. By this means its temperature and pressure are highly increased, as in passing through the lower portion of the central water-leg it is brought into the direct and close influence of the fire.

Various changes may be made in the arrangement and relation of the cylinders without departing from the spirit of the invention. Instead of having a single cylinder with a series of cylinders surrounding the same, the cylinders may be arranged in parallel rows,

as shown in Fig. 2, the outer rows being in communication with the intermediate row, which in turn communicates by separate central tubes with the steam-pipe above.

The arrangement of the fire-flues and water-legs differs somewhat from those shown in Fig. 1. In the latter the water-legs of the outer cylinders depend from the inner half of the cylinders, so as to be in close proximity to the fires, and these legs have on their outer surfaces longitudinal webs or flanges to increase the heating-surface. In the modification illustrated in Fig. 2 the water-legs depend from the outer halves of the cylinders, while the fire-flues extend through the inner halves. The steam or water of circulation is conducted to the intermediate cylinders through branches connected with the cylinders on the outer side of their common diameters.

All the cylinders in the modification are provided with radial external webs, l , corresponding to those on the water-legs of Fig. 1 and for the same purpose.

Having described my invention, what I claim, and desire to secure by Letters Patent, is—

1. In a steam-generator, the combination, with water-legs, of external longitudinal flanges or webs formed thereon or attached thereto divided into sections, substantially as described.

2. In a steam-generator, the combination, with a series of cylinders, E', of a central or intermediate cylinder or cylinders, the latter being elongated or extended into the fire-space and above the water-level, so as to constitute a superheater, substantially as described.

3. In a steam-generator, the combination, with the cylinder E, having the depending leg f' , continued or extended to near the top of the cylinder, of the internal tube, k , terminating near the bottom of said leg and communicating therewith and with the steam-pipe L, substantially as described.

4. A non-conducting casing for steam-boilers, consisting of two metallic cylinders, A' and C', inclosed one within the other and each formed with a dome, the whole being supported upon a bed-plate having air-passages d , each of said cylinders and domes being lined with non-conducting fabric, and a cold-air space communicating solely with the outer air at the base of the structure, being left between the lining of the outer cylinder and the surface of the inner cylinder, substantially as described.

In testimony that I claim the foregoing I have hereunto set my hand this 14th day of November, 1887.

LUCIUS D. COPELAND.
